UNITED STATES PATENT OFFICE.

JOHN H. GILMAN, OF OTTAWA, ILLINOIS, ASSIGNOR TO KING & HAMILTON COMPANY, OF OTTAWA, ILLINOIS, A CORPORATION OF ILLINOIS.

CORN-SHELLER.

SPECIFICATION forming part of Letters Patent No. 761,068, dated May 31, 1904.

Application filed January 22, 1903. Serial No. 140,070. (No model.)

To all whom it may concern:

Be it known that I, JOHN H. GILMAN, a citizen of the United States, residing at Ottawa, in the county of LaSalle and State of Illinois, have 5 invented certain new and useful Improvements in Corn-Shellers, of which the following is a specification.

My invention relates to corn-shellers, and particularly to that class wherein a shelling-drum revolves within a suitable shelling-cylinder.

The object of the invention is to provide a new and improved deflector located on the cylinder or casing at or near the exit end of the 15 machine, whereby the cobs are positively discharged from the machine.

In the accompanying drawings, which form a part of the application, and in which the same reference-letters denote the same or corresponding parts in the various views, Figure 1 is a vertical sectional view of a corn-sheller with the shelling-drum in side elevation provided with my improvement. Fig. 2 is a vertical cross-sectional view of Fig. 1 at the exit 25 end of the drum. Fig. 3 is a sectional view on the line 3-3 of Fig. 2, the view being taken in the direction of the small arrow. Fig. 4 is a detail perspective of the deflector of the preceding figures. Fig. 5 is a detail view showing a modification; and Fig. 6 is a horizontal section on the line 6-6 of Fig. 2, showing the inclination of the deflector with respect to the shelling-drum, the latter being illustrated in broken lines.

Referring to the drawings by letter, the reference-letter A denotes the usual upright frame of the machine, to each end of which a semicircular plate a is secured, which is provided with seats a' . Between the end plates 35 a plurality of semicircular rings a^2 are mounted on the side bars a^3 , which are bolted to the frame in any suitable manner. The rings are provided with seats corresponding to the seats in the end plates, and horizontal rods or ribs 40 a^4 are supported in these seats to constitute the skeleton bottom of the shelling-cylinder, the spaces between the adjacent ribs being of

any suitable width to allow the chaff and shelled corn to readily pass through while retaining the cobs. The shelling-drum B is 50 suitably mounted in bearings on the frame and revolves within the cylinder in the direction of the large arrows of Figs. 1 and 2, being driven by any suitable means. The drum is provided with a plurality of rows of shell- 55 ing-teeth b , arranged spirally along the length of the drum, as clearly shown in Fig. 1, and at its feed or inlet end with oppositely-disposed curved plates b' . Near the rear or outlet end of the drum I prefer to employ oppositely-disposed curved wings b^2 , the plates and 60 wings acting as shelling elements and being suitably bolted to the drum, so as to present their plain sides or faces to the material in the machine, and being disposed and shaped 65 to be in extension of the spiral lines of the teeth b .

At the front or feed end of the machine the frame A is preferably extended upwardly, and the hood C of the casing or cylinder is secured to this portion of the framework inclosing the feed-aperture and extending over a portion of the drum to form a hopper for feeding the ears into the machine, the sides of this hood being suitably secured at their 70 lower edges to the side bars a^3 . The upper portion of the casing or shelling-cylinder is in the form of a semicylindrical cover C, which is secured at its front end to the roof 75 of the hopper and at its rear end to the framework, being attached at its sides to the side bars a^3 .

Near the exit or discharge end of the machine and preferably upon the cover I locate a suitable deflector D, as shown in Fig. 6, 85 which is set obliquely at an angle to the axial line of the drum and to form a more or less acute angle with the line of the pitch of the teeth and wings of the drum. The deflector may be of any suitable form, and preferably 90 is constituted of a blade or rib of substantially rectangular form in side elevation, and preferably is provided with a curved lower edge corresponding to the curvature of the

drum. The deflector is supported on the cylinder near the rear end and in any suitable manner. For example, as shown in Fig. 5, the deflector is provided with a flange d^1 , by 5 which it is bolted to the cylinder, it being understood that the flange is preferably upon the rear side or inoperative face of the deflector, or the deflector may be supported by a suitable housing d^2 , which is bolted to the 10 cylinder and receives the deflector. The deflector may be made adjustable, as by providing the housing with a slot or guide d^3 to receive the deflector, which may be moved therein by any suitable means, such as the 15 hand-wheel d^4 , which is revolvably mounted and supported against displacement on the housing, as by means of the opposite bearings d^5 and d^6 or any other suitable means, and has a threaded engagement with the stem 20 d^7 , which is suitably connected to the upper portion of the deflector. In practice the deflector may be formed with an integral upper head d^8 , which enters the guide of the housing a sufficient distance to have an extended 25 bearing therein, whereby the deflector is securely held against displacement against the impact of the cobs as they are swept against it. The housing need not be of the same length as the deflector, in which case the deflector may project through the end of the 30 housing, as at d^9 . By rotating the hand-wheel in one direction the deflector may be set down to operative position, and by reversing the rotation of the wheel it may be 35 withdrawn within the housing, it being apparent that its adjustment with relation to the drum may be varied and regulated as the occasion requires and that it is securely held in any desired position. When corn is badly 40 husked, the deflector is set down nearer to the cylinder than when clean corn is treated, as in the former case the husks choke the machine at the discharge end unless the deflector is employed. It is obvious that the means of 45 adjusting the deflector may be varied without departing from my invention and that the form of the deflector may be changed.

In the operation of the machine the ears of corn are fed into the hopper, and as the corn 50 is shelled between the drum and cylinder the cobs are carried by the spiral plates and teeth toward the rear of the machine, the shelled corn dropping through the skeleton bottom of the shelling-cylinder. When the 55 cobs approach the exit of the machine, they are swept and carried by the teeth against the deflector, which acts to positively expel them at the rear. It is obvious that when unhusked corn is treated the husks will be 60 expelled by the deflector in like manner as the cobs. In practical work the cobs have a tendency to clog at the discharge or outlet, whereby the machine becomes quickly choked and obstructed, and the provision of the ob-

lique deflector overcomes this objection, as it 65 obviates all danger of congestion by the cobs by reason of the fact that, in conjunction with the spiral projections on the drum, it forms a chute or channel that gradually is reduced in size as the point where the projections cross 70 the deflector approaches the rear end, and the cobs are crowded along this channel and positively directed out of the machine. It is obvious that rear wings b^1 are of advantage in 75 coöperating with the deflector, as their action in carrying the cobs against the deflector is more certain than that of the teeth, and for this reason I prefer to employ them.

In the construction of the machine it is obvious 80 that the deflector may be set at any angle to the axial line of the drum or to the pitch of the projections thereon.

In practice the shelling of the corn takes place at all points between the drum and cylinder, and under normal conditions the corn 85 is all shelled off the cobs before the cobs and husks reach the deflector and most of the corn has passed through the openings in the lower part of the cylinder. There are times, however, when the corn is in such condition as to 90 make the shelling of it more difficult, and when in this condition a portion of the cobs reach the location or position of the deflector with some corn still on them. When this condition prevails, the deflector is not desired, and it is then 95 entirely withdrawn into its housing or removed, according to the form employed, to permit the retention of the cobs in the cylinder to complete the shelling operation. The absence of the deflector greatly reduces the 100 capacity of the machine and is not resorted to except in extreme cases. It is obvious that for this purpose the deflector of Fig. 5 will be 105 removably attached to the cylinder.

Having described my invention, I claim— 105

1. In combination with a corn-sheller comprising a cylinder and a shelling-drum rotating therein, of a deflector within and supported by the cylinder and projecting toward the drum and set obliquely at an angle to the 110 axial line of the drum.

2. In combination with a corn-sheller comprising a cylinder and a shelling-drum rotating therein, of a deflector within and supported by the cylinder and coacting with the 115 drum to expel the cobs and being in a plane obliquely at an angle to the axial line of the drum.

3. In combination with a corn-sheller comprising a cylinder and a shelling-drum rotating therein and provided with teeth disposed in spiral lines, of a deflecting-plate within and supported by the cylinder and being in a plane obliquely at an angle to the axial line of the 120 drum and having its lower edge curved to conform to the curvature of the drum.

4. In a corn-sheller, the combination with a cylinder, a drum having teeth disposed in

spiral lines, and wings at its rear end, of a deflector secured within the cylinder and at an angle to the axis of the drum.

5. In a corn-sheller, the combination with a cylinder, a drum having teeth disposed in spiral lines, and wings at the rear end of the drum and in extension of the lines of teeth, of a deflector attached to the cover of and

within the cylinder and having its working face at an angle to the axial line of the drum. 10

In testimony whereof I affix my signature in presence of two witnesses.

JOHN H. GILMAN.
